UNITED STATES PATENT OFFICE.

JOHN F. WHITE, OF BLOOMINGTON, ILLINOIS, ASSIGNOR TO PORTABLE WAGON DUMP AND ELEVATOR COMPANY, A CORPORATION OF ILLINOIS.

WAGON-DUMP.

No. 873,814.

Specification of Letters Patent.

Patented Dec. 17, 1907.

Application filed August 6, 1903. Serial No. 168,437.

To all whom it may concern:

Be it known that I, JOHN F. WHITE, citizen of the United States, residing at Bloomington, in the county of McLean and State 5 of Illinois, have invented certain new and useful Improvements in Wagon-Dumps, of which the following is a specification, reference being had therein to the accompanying drawing.

10 This invention relates to an improvement in unloading apparatus, more particularly to that class or type of apparatus which is designed for use in connection with a wagon or other vehicle in which material is to be transported, and which wagon or vehicle is required to be dumped for unloading purposes. At the present time many so called wagon dumps have been suggested and associated with such dumps usually endless 15 carriers or elevators have been employed onto which the material is dumped and by which the material is transported to the bin, granary, or other depository.

In the prior art it has been usual to provide a so called wagon dump with means for raising the forward part of the wagon so as to discharge the load therein from the tail end of the wagon and suitable drags, so called, have been employed for receiving the material from the wagon. These drags have been provided with endless conveyers and the material has been conveyed thereby into an elevating carrier. These elevating carriers have in some instances been arranged 30 parallel with the dump and in some instances have been arranged at right angles to the dump according to the position of the crib or granary. It has been usual to raise and lower the elevators so as to accommodate 35 them to granaries and bins of different heights. The driving power for the elevator, drag, and the dumping device has usually been in the form of horse power so coupled with the various members that they 40 are all driven or actuated by a single horse power or motor.

My invention relates to improvements in this latter class of machines and the objects of the invention may be stated briefly as follows: first, to so construct an unloading device that the elevator or conveyer may be adjusted to extend in a direction either transverse or parallel with the platform of the machine; second, to provide suitable means whereby the transfer drag can be operated

with equal efficiency irrespective of the adjustment or position of the elevator proper; third, to provide suitable mechanism for actuating the dump with automatic actuating means for governing the movement of said 60 mechanism; fourth, to provide a dump with means for raising and lowering the same, and means for automatically governing the raising and lowering of the dump which automatic means are actuated independent of the 65 dump; fifth, to provide improved mechanism for governing the upward movement of the dump, releasing the same, and permitting its adjustment for lowering movement; sixth, a dumping device with means for automatically 70 governing the same and associated with said automatic means, suitable mechanism for variably actuating the dump in its up and down movement respectively; and finally to provide an unloading device which 75 will possess the necessary characteristics rendering the same largely automatic dispensing with manual labor and the requirement of specific attention for regulation and movement of the various parts.

In the drawings accompanying these specifications I have shown an embodiment of the apparatus containing the invention presently to be described, but it is to be understood that the illustrated machine is susceptible of 80 wide changes and modifications, and in fact the parts may be entirely changed, some modified, and some omitted, without departing from the principle of the invention, the illustrated structure being employed in this 85 specification more for the purpose of illustrating the principle of the invention than the exact details, and therefore I do not wish to be limited in my protection to the specific 90 construction shown.

Figure 1 is a side elevation of a machine embodying the invention; Fig. 2 is a plan view partly in section; Fig. 3 is a perspective view of a portion of the machine; Fig. 4 is a detail view of the lower portion of the elevator; Fig. 5 is a sectional view of the gearing for the dump showing parts in elevation. Fig. 6 is a section through the standards; Fig. 7 is a detail view of a portion of the elevator and drag; Fig. 8 is a plan view of the 100 frame.

In the drawings the platform A is supported on suitable frame work, and has at its opposite ends drive-ways. At one side of the platform, at the rear, is a supporting frame- 110

work B carrying thereon a removable boxing B' into which the lower end of the elevator or conveyer C extends, the same being conveniently mounted on its flight driving shaft one side of the boxing being cut away for that purpose. At right angles to the elevator is the drag D of any improved type having an endless conveyer therein. The end of this drag is let into the side of the boxing B' and is held directly above the lower boot or end of the elevator, the drag standing at right angles to the elevator. Suitable gearing, as for instance a sprocket chain b extends from the driving shaft A' over suitable sprockets, one being on the shaft and the other being on the driving shaft of the drag. To actuate the endless flight of the elevator, conveniently I extend a transverse shaft A² below the platform, mount the same in suitable bearings, and couple the same with the shaft A' by suitable bevel gears a', a², and on the shaft A² is mounted a sprocket wheel a³ over which a chain passes over the sprocket wheel a⁴ on the driving shaft of the elevator. In this connection I have also found it advantageous to provide the ends of the shafts A' and A² with squared ends with which the power driven shaft from a suitable horse power or motor can be coupled. As shown in the drawings it will be seen that the shaft A' extends the length of the machine and that both ends are provided with squared extensions so that I am enabled to couple the horse power up with the machine at three different points, namely, to either end of the shaft A' or to the end of the shaft A². This is convenient as it permits the use of a machine in places where it would be inconvenient to utilize the horse power were it permitted application to one point only.

In constructing the parts of the elevator and drag as above described, I have found it necessary to cut out a triangular section b³ from the side of the elevator boot or base so that the end of the drag will project sufficiently over the edge of the base of the elevator. This small cut out section b³ is adapted to be replaced and held in place by suitable straps such as b⁴, for purposes presently to be stated. It will also be noticed by the above construction that the elevator stands parallel with the machine or platform while the drag stands at right angles thereto, the power driven shaft being arranged to actuate the flights of both the elevator and drag. Should, however, the conditions demand that the elevator be adjusted to a point at right angles to the platform, the construction which I have above described will permit of such readjustment, with this variation: The boxing B' may be conveniently removed and a V-shaped portion b⁵ replaced to complete the continuity of the sides of the elevator, the elevator is then turned at right angles and bolted or secured by other suitable

means in place to the frame B suitable saddles B² conveniently being employed. The driving shaft carrying the sprocket wheel for driving the flights of the elevator will stand parallel with the platform while the driving shaft of the drag is in the position it formerly occupied. To transmit the power of the shaft A' to the driving shaft of the elevator I place on the former a supplemental sprocket wheel a⁵ over which the driving chain passes, after passing over the sprocket on the elevator, as shown in Fig. 7. The elevator is then supported in the usual way by a derrick or other means, and the parts are operated through the driving shaft. 80

At the front ends of the machine, at opposite sides are the standards E, F, the former being somewhat larger in proportion than the latter and between these standards is the elevating frame G conveniently composed of 85 parallel side bars and connecting end bars in a well known manner. To elevate and lower the elevating frame suitable cables e, f, are attached to bails connected with the ends of the frame, and pass up over suitable pulleys e², e³ mounted on the top cross-bars of the uprights. These chains are carried down between the vertical bars of the uprights or standards and have their lower ends connected with suitable drums E', F' mounted on 90 the cross-shaft F². By turning the drums the chains are wound thereon and the elevating frame is moved up and down as the case may be. To guide the elevating frame in its movement suitable rolls or wheels g 100 are employed working against the outer faces of the side posts of the standards, as shown, which are carried by the elevating frame. To actuate the drum shaft F², at one end it is equipped with a suitable worm 105 wheel F³ which meshes with a worm F⁴, the parts being mounted in suitable bearings in the casting H, suitably bolted to the frame work and standards. The casting H is formed of three or more branches, the upper 110 ends of each constituting bearings for a parallel loose shaft J, the extreme rear end of which is mounted in a fixed bearing j on the platform. The shaft J has fixedly secured thereto a clutch collar K which in turn is 115 loosely engaged by a forked lever K' pivoted at K² on the cross-bar e⁴ on the standard E. The rocking of this lever K' moves the shaft J longitudinally and brings the clutching ends of the collar K into clutching engagement with complementary faces of the bevel pinions L, L' which are loosely mounted on the shaft J. These pinions L, L' are in mesh 120 with a bevel pinion L² mounted on the outer end of the worm gear F⁴, so that as the pinions L, or L' are coupled to the shaft J by the clutching faces thereof and the clutching collar on the shaft, the movement of the shaft J will be transmitted to the wheels driving the worm gear in the direction of the wheel 125 130

which is being actuated. To drive the shaft J, I have provided suitable sprocket wheels J³, J⁴ the former being of greater diameter than the latter. These wheels are loosely mounted on the shaft J and are held in their relative positions by a suitable sleeve J⁵ surrounding a movable clutch member J⁶ keyed to the shaft J. This clutch member being keyed to the shaft, is movable with the shaft longitudinally so that as the shaft is moved it will bring the clutch member K as well as the clutch member J⁶ into engagement with one of the sprocket wheels J³, J⁴, and one of the bevel gears L, L'. The sprocket wheels are each provided with clutching faces to correspond with the clutching member J⁶. On the shaft A' are placed sprocket wheels M and N the former being relatively smaller than the latter and being in line with the sprocket wheel J³ on the shaft J while the sprocket wheel N being the larger of the two on the shaft A' is associated with or in line with that of the smaller sprocket wheel J⁴ on the shaft J. Suitable drive chains pass over the various sprocket wheels as shown.

By the above arrangement it will be seen that when the dumping frame is to be elevated it is only necessary to adjust the lever K' to couple the larger sprocket wheel J³ with the shaft J thereby reducing the movement of the shaft J owing to the differential sizes of the gearing or sprockets. The worm gear is thereby slowly moved which action slowly or gradually winds up the elevating chains and the dumping frame. This slow movement is necessary and desirable so that the contents of the wagon will be discharged and simultaneously carried off by the drag and the elevator, the discharge from the wagon being equal to the capacity of the elevator. When the dumping frame is to be lowered the shaft J is shifted in an opposite direction and owing to the differential sizes of the gearing which are by that movement coupled, the frame is lowered very rapidly but regularly, thus saving considerable time in replacing the wagon after the load has been emptied.

The clutch and adjusting arrangement of the above construction may be advantageously adjusted by hand if found desirable, but I have found it advantageous to acquire such movement through the automatic action of the machine, and to this end have provided the following mechanism: Mounted on suitable cross-bars O in the upright or standard E, slightly above the end of the lever K' is a wheel P, the same being carried by a shaft P' mounted in bearings in the cross bars and having its outer end bent down into the form of a crank, the outer end of which engages through an elongated slot p in the end of the lever K'. The opposite end of the shaft P' is bent upward and thence inward to a point directly above the periphery of the

wheel P. Passing over the wheel P is a sprocket chain or other convenient form of driving belt Q, its lower end passing over a sprocket wheel R mounted on the shaft F² and receiving its movement therefrom. The chain Q is provided with trip projections or links q, q', extending out laterally therefrom and designed to engage the inturned end p' of the end of the shaft P' as the chain is moved. These trip projections or links are so positioned on the chain Q that as the dumping frame is elevated and reaches the limit of its upward movement the projection q will come in contact with the projecting end p' of the shaft P' forcing it rearward, rocking the crank arm on the opposite end of the shaft and thereby rocking the lever K', shifting the clutching mechanism so that by moving the crank by hand a further distance it will immediately throw into action the mechanism for lowering the dumping frame. The frame will then immediately descend with relatively great rapidity until the projection q' comes in contact with the end p' of the shaft P' changing the position of the crank on the latter and stopping the descent and setting the machine for adjustment to operate in a reverse direction. By this construction the machine for elevating the front end of the wagon is made automatic in its stopping action independent of the frame, its travel upward being limited, and the movement being reversed through the lever K' while its travel downward is also limited and reversed by the lever and its clutch. The lever K' is automatically moved initially and the shifting movement is completed by the operator. It will be understood that while this part of the invention as shown in the form described, is satisfactory, the same result can probably be accomplished by widely different mechanism. It is this independent governing of the dumping frame which I believe to be broadly new in this art.

When the elevator is in the position shown in Fig. 1, it is necessary to have some provision for raising and lowering the same to change its angularity. This I have accomplished by providing the standard E with a guide-way s in which works a vertically reciprocating bar S. This bar S carries on its upper end a shaft s' provided with suitable wheels s² on which the lower edge of the elevator C rests. By moving the bar S up and down, the elevator trough is also moved up and down, and to accomplish this movement I mount in the standard E a drum T to which a suitable rope or cable T' is attached, the same passing up over an idler wheel t', and thence down and is secured to the lower end of the bar S. On the end of the shaft of the drum T is a crank, and a suitable ratchet wheel T² with which a pawl T³ engages. The bar S is guided in its up and down movement by having a suitable track S² resting

against the flanges of the idler wheel $t^{\prime}$ so that as the bar is raised or lowered, owing to the inclination of the elevator the tendency of the bar is toward the front of the machine, 5 and therefore against the idler pulley, it will meet with no perceptible resistance and the elevator can be handled easily, moved up and down to assume different inclinations.

In view of the description with a general 10 reference to the operation it is thought that a specific general description of the operation of the apparatus will be unnecessary. It will be noticed however, that in connection with the lever K a suitable hand bar U may 15 be employed extending to the rear of the machine in convenient reach of the operator, and also that a suitable chute such as shown at W may be employed at the upper end of the elevator, when desired.

20 I am aware that dump actuating mechanisms have heretofore been governed in their elevating movement by a trip which is struck by the elevating frame, thereby limiting the up movement of the dump, but as far as I am 25 advised I am the first to actuate a trip, stopping and reversing means by mechanism actuated independently of the elevating frame or dump.

Having thus described the invention what 30 is claimed as new and desired to be secured by Letters Patent is:—

1. In a wagon unloading apparatus, the combination with a suitable support, of an elevator removably connected therewith, a 35 conveyer associated with the elevator, mechanism for actuating the elevator and the conveyer, and means whereby the position of the elevator can be changed from a position parallel with the support to a position outwardly at an angle to the support and the converse relative to the conveyer and actuated in its changed position.

2. In a wagon unloading apparatus, the combination with a platform, of an elevator 45 arranged parallel therewith and mounted to be adjusted outwardly at an angle thereto, a drag arranged at an angle to the elevator, means for driving the drag and the elevator, and means for actuating the elevator when 50 the latter is adjusted outwardly at an angle to the support.

3. In a wagon unloading apparatus, the combination with a platform, of a driving shaft, a counter driving shaft geared thereto, 55 an elevator, removably secured to the platform, a drag, and means on the driving and counter shafts for actuating the elevator.

4. In a wagon unloading apparatus, the combination with elevating means and a 60 dumping means, of a power shaft having its opposite ends fashioned for coupling with a suitable motor, and a counter shaft geared to the driving shaft and also provided with means for coupling the same to the motor.

65 5. In a wagon dumping apparatus, the

combination with an elevator having a removable member at its lower end, a drag arranged to project into the space occupied by the said removable member, a boxing surrounding the end of the drag and elevator, 70 and means for driving the drag and elevator.

6. In a wagon dump, the combination with dumping instrumentalities, of means for actuating the same, and connected mechanism acting independently to interrupt the 75 up and down movement of said dumping instrumentalities.

7. In a wagon dump, the combination with dumping instrumentalities on which a part of the wagon is adapted to rest, of 80 means for elevating said instrumentalities, and mechanism acting independent of said dumping instrumentalities for limiting the upward movement of said dumping instrumentalities.

8. In a wagon dump, the combination with a dumping frame, of means for raising and lowering the same, connected mechanism actuated directly by said raising and lowering means for limiting the up and down 90 movement of said dumping frame.

85 9. In a wagon dump, the combination with an elevating device for the front end of a wagon, of mechanism for differentially raising and lowering the said device, and 95 mechanism associated with said raising and lowering mechanism for reversing and checking the movement of the latter.

10. In a wagon dump the combination with raising means, of mechanism for elevating the same, governing mechanism actuated by said elevating mechanism independent of the raising means for limiting the movement of the latter, and means independent of the raising means for moving the 105 governing means.

11. In a wagon dump the combination with means for supporting the front end of a wagon and raising and lowering mechanism thereof, of means acting automatically for interrupting the movement of said mechanism at predetermined points and actuated directly by said mechanism, and manually operative means for checking the movement of the raising and lowering mechanism at different points substantially as described.

110 12. In a wagon dump, the combination with standards, of an elevating frame located therebetween, a drum shaft, chains connecting the drums with the frame, a power shaft, 120 differential gearing connecting the power shaft with the drum shaft, and clutching mechanism interposed between the gearing, substantially as described.

125 13. In a wagon dump, the combination with a dumping frame, means for actuating the same, of a sliding shaft having a clutch thereon, gears adapted to be engaged by said clutch for imparting reverse movements to the shaft, a driving shaft, differential driving 130

connection between the same and said movable shaft, and a clutch for said differential driving connection.

14. In a wagon dump the combination with 5 a power shaft and an elevating frame, of means for actuating the latter by the former, a clutch mechanism for reversing the movement of the frame, and mechanism comprising an endless member having projections 10 thereon and a lever having a complementary projection with which the said other projections engage for shifting said clutch during the movement of the frame.

15. In a wagon dump, the combination 15 with standards, an elevating frame, a counter-shaft, connections between the counter-shaft and the frame, a shifting gear mechanism associated with said counter-shaft, a power shaft for driving the gear, a clutch 20 mechanism, an endless chain connected with the counter-shaft, a lever connected with the clutch mechanism, and means actuated by the chain for shifting the lever.

16. In a wagon dump, the combination 25 with a platform and dumping means, comprising standards, and an elevating frame therebetween, of an elevator connected with the platform, a movable bar carried by a standard, on the upper end of which the 30 elevator rests, and means on the standard for raising and lowering the bar.

17. In a wagon dump, the combination with a platform, of an elevator parallel therewith at one side thereof, a dumping standard, 35 a bar slidably supported in said standard, wheels on the upper end of the bar on which the elevator rests, and means for raising and lowering the bar to vary the inclination of the elevator.

40 18. In a device of the class described, the combination of a wagon receiving platform, gearing for raising and lowering the platform, said gearing being provided with a shiftable clutch for throwing it out of operation, a shifting device connected with the clutch, and an endless connection operated by the gearing and provided with means for actuating the shifting device for automatically stopping the platform, substantially as described.

50 19. In a device of the class described, the combination of a platform, means connected with the platform for raising and lowering the same and provided with a clutch, a shifting lever connected with the clutch, and an endless connection operated by the said means and provided with means for shifting the lever to operate the clutch automatically, substantially as described.

60 20. In a device of the class described, the combination of a platform, means for raising and lowering the platform provided with a clutch, a shifting lever connected with the clutch, and sprocket gearing operated by the 65 said means and provided with a sprocket

chain having means for actuating the lever to automatically operate the clutch, substantially as described.

21. In a device of the class described, the combination of elevating means having two sets of gearing, and an intermediate clutch member for engagement with either set of gearing, a shifting lever connected with the clutch member, and an endless connection operated by the said elevating means and provided with means for alternately engaging the shifting lever to operate the clutch automatically, substantially as described. 70 75

22. In a wagon dump the combination with means for supporting the front end of a wagon and raising and lowering mechanism thereof, of means actuated directly by said mechanism and acting automatically to interrupt the driving up movement of the mechanism at a predetermined point and manually operative means for checking the movement of the raising and lowering mechanism at different points. 80 85

23. In a device of the class described, the combination with a pair of standards suitably connected at their lower ends and a vertically movable platform guided therein, of pulleys supported in said standards, a shaft journaled at the bottom of said standards and extending from one to the other, drums 90 upon said shaft, flexible connecting devices secured to the platform and extending over the pulleys to the drums, a continuously rotating shaft, a countershaft, suitable gearing between said continuously rotating shaft 100 and the counter shaft adapted to rotate said countershaft in either direction, means operated during the movement of the platform in either direction for throwing said gearing out of engagement, a worm upon said countershaft, a worm gear upon the drum shaft in engagement with said worm said worm and gear connection being adapted to furnish means to hold the platform in its raised position when the clutch has been disengaged. 105 110

24. In a device of the class described, the combination of an elevating frame, hoisting mechanism for raising and lowering the frame, power gearing connected with the hoisting mechanism and provided with a clutch for throwing it out of operation, a shifting device connected with the clutch, and means independent of the elevating frame and the hoisting mechanism and operated directly by the power gearing for actuating the shifting device to stop the elevating frame at the end of its upward movement, substantially as described. 115 120

25. In a device of the class described, the combination of an elevating frame, hoisting mechanism for raising and lowering the same, power gearing connected with the hoisting mechanism and provided with a shiftable clutch, a shifting lever, a device to engage the lever to shift the same, said de- 125 130

vice being located outside of the path of the elevating frame and mechanism connected to and operated directly by the power gearing to bring the device into contact with the shifting lever for stopping the elevating frame at the limit of its upward and downward movements, substantially as described.

26. In a device of the class described, the combination with a base, a platform adapted 10 to be elevated and lowered on the said base, a drive shaft, a worm-wheel shaft, differential gearing connecting the drive shaft with the worm-wheel shaft, means for controlling the connection of the drive shaft with the 15 worm-wheel shaft, and suitable connections between the last mentioned shaft and said platform, substantially as specified.

27. In raising and lowering mechanism, a worm shaft and worm, a reversible drive connected with said shaft, a drum shaft and 20 drum, a worm wheel on said drum shaft in mesh with the worm aforesaid, and an endless belting driven by said drum shaft and provided with means for automatically controlling the drive connected with the worm 25 shaft for checking the movement of said shaft.

In testimony whereof I affix my signature in presence of two witnesses.
